W. C. GARNER

WATER HEATER

Filed Dec. 23, 1922

INVENTOR
WELBORN C. GARNER.

BY Fletcher & Co.
ATTYS.

UNITED STATES PATENT OFFICE.

WELBORN CLAY GARNER, OF SEATTLE, WASHINGTON.

WATER HEATER.

Application filed December 23, 1922. Serial No. 608,743.

To all whom it may concern:

Be it known that I, WELBORN CLAY GARNER, a subject of the King of Great Britain, and now residing at the city of Seattle, in 5 the State of Washington, one of the United States of America, have invented certain new and useful Improvements in Water Heaters, of which the following is a specification.

10 This invention relates to improvements in water heaters, and the objects of the invention are to effect increased economy in the transference of heat from the heat source to the water to be heated and, further, 15 to enable the character of the heat source to be changed, if desired.

Further objects are to effect concentration in the application of a heating medium to the water to be heated whereby the speed of 20 heating may be increased.

Further objects still are generally to improve and simplify the construction of the device and to better adapt it to perform the functions required of it.

25 And it consists essentially of the improved construction hereinafter described in detail in the accompanying specification and drawings.

In the drawings:

30 Figure 1 is a sectional elevation of an embodiment of the invention.

Figure 2 is a cross-section on the line 2—2 of Figure 1.

35 Figure 3 is an elevation of the heating element.

In the drawings, like characters of reference indicate corresponding parts in all the figures.

Referring to the drawings:

40 A indicates the hot water boiler having an intake pipe 10 and an outlet pipe 11. The side of the boiler may be provided with the usual water glass 12. B indicates the heating element, and one of the features of the invention lies in the fact that the heating element may be readily replaced and gas may be substituted for electricity or other heating means.

45 I have illustrated a form of electrical heating element including a core 13 having a cylindrical portion 15, the electric heating resistance being wound upon the spiral grooves 16 in the usual manner and being connected to terminal conductors 17 and 18 which lead to cords 19 and a plug socket 20.

The cylindrical portion 14 is about one-third of the height of the heating element and is formed with a plurality of concaved reflecting surfaces 21, from which the heat is designed to be reflected as hereinafter described, the said reflecting surfaces being covered with a metal reflecting member 22 secured to or forming part of the base 23 which supports the core 13, and itself rests upon the bottom plate 24 of the boiler, the said bottom plate having an outlet conduit or neck 25 through which the cord 19 passes.

The core 13 fits closely to a casing 26 of similar shape to the core, and having a vent pipe 27 at the top thereof which leads through the top of the boiler and is normally closed by a screw-threaded cap 28. The water to be heated is designed to circulate on the outside of the casing 26 being guided by a spiral baffle 28 which extends between the casing 26 and a second enclosing casing 29, the upper end of which is provided with a relatively large screw-threaded neck 30 which has screw-threaded engagement with the top plate 31 of a supporting member 32 of conoidal shape, the lower extremities of which are connected to the bottom of the boiler as by means of bolts 32^a which pass through the side wall 33 of the boiler as well as through flanges 34 and 35 formed on the member 32 and the bottom plate 24 respectively.

The space between the members 29 and 32 is filled with air and is designed to form heat insulation. The heating circuit for the water boiler is completed by a conduit 36 which extends from the outlet 11 to a T-union 36^a from which a pipe 37 leads to an elbow 38 connected to the inlet conduit 39 which opens in the water heating chamber 40 constituted by the space between the casings 26 and 29. The water being forced to pass by the baffle 28 in a spiral manner around the heating element B is heated thereby and passes out through the neck 30 into the boiler. The water to be drawn off from the boiler is drawn through a conduit 41 connected to the union 36^a and the said union preferably including a check valve which prevents withdrawal of the water from the heating chamber 40 through the pipe 37.

It will be seen that, by loosening the bolts 32^a and unscrewing the threaded neck 30, the heating element as a whole may be removed and, furthermore, that the member

B may be readily removed from the interior of the casings 26 and 29, and, when this is done, any alternative form of heating means might be placed within the casing 26.

- 5 The reflectors 22 will cause reflecting of heat from the cylindrical portion of the core B to the inner side of the surface of the casing 26 over the outer surface of which the water to be heated passes.
- 10 It will be further observed that the whole heating element is within the boiler A. The heater may be used for heating water or other fluids or for making steam.

As many changes could be made in the 15 above construction and many apparently widely different embodiments of my invention within the scope of the claims, constructed without departing from the spirit or scope thereof, it is intended that all matter contained in the accompanying drawings and specification shall be interpreted as illustrative and not in a limiting sense.

What I claim as my invention is:

1. A water heater comprising a boiler, a 25 tapered supporting member on the bottom of the boiler, a tapered casing supported from the supporting member being spaced therefrom by an air space, and a heating element within the casing.
- 30 2. A water heater comprising a boiler, a tapered supporting member on the bottom of the boiler, a tapered casing supported from the supporting member being spaced therefrom by an air space, a heating element within the casing, a water chamber between the casing and the heating element, and means for causing circulation of water from the boiler through the water chamber.
- 35 3. A water heater comprising a boiler, a 40 tapered supporting member on the bottom of the boiler, a tapered casing supported from the supporting member being spaced

therefrom by an air space, a heating element within the casing, a water chamber between the casing and the heating element, means 45 for causing circulation of water from the boiler through the water chamber, and a spiral baffle in the said water chamber.

4. In a water heater, a heating element comprising a cylindrical portion having reflecting sections and a spiral portion, an 50 electrical resistance on the spiral portion, a water heating casing surrounding the heating element, and means for circulating water in the water heating casing.

5. A water heater of the character described comprising a boiler having side walls and a removable bottom conical supporting member secured to the side walls of the boiler having a threaded top plate, a casing 60 having a threaded neck engaged with the top plate and having its body portion separated therefrom, a second casing within the first casing spaced therefrom to constitute a water heating chamber, heating means 65 within the second mentioned casing, and means for circulating water in the water chamber.

6. The arrangement as claimed in claim 6, in which the heating element comprises a 70 core having a cylindrical portion and a conical portion, and an electrical resistance on the conical portion.

7. In a water heater, an electric heating element comprising a core formed with a 75 cylindrical portion with concave reflecting surfaces, and a conical portion having electrical resistance thereon.

In witness whereof I have hereunto set my hand in the presence of two witnesses.

WELBORN CLAY GARNER.
